UNITED STATES PATENT OFFICE.

ALFRED JENSEN, OF NEW YORK, N. Y., ASSIGNOR TO ELLIOTT-FISHER COMPANY, A CORPORATION OF DELAWARE.

CARBON GUARD FOR MANIFOLDING MACHINES.

Application filed December 31, 1925. Serial No. 78,682.

My invention relates to manifolding machines and more specifically to improvements in carbon guards for such machines.

One object of the invention is to provide a simple device which will protect the interlocking edges of interleaved or otherwise contacting strips of materials such as carbons and paper sheets, against mutilation when moved in relatively angular directions. 10 To the accomplishment of this and other objects presently apparent, the following description, and the accompanying drawings discloses a preferred embodiment of my invention.

15 In said drawings:

Figure 1 is a top plan view, partly broken away, illustrating the application of my invention to a well-known type of flat platen manifolding machine.

20 Figure 2 is an enlarged detail view in longitudinal section.

Figure 3 is a perspective view showing the ends of a guard embracing the edge of the carbon.

25 Figure 4 is a view of a blank from which the guard is formed.

Figure 5 is a fragmentary plan view showing the manner of attachment of the guard to the carrier, and

30 Figure 6 is a detail longitudinal sectional view showing the ends of the guard embracing the edge of the carbon.

The particular type of manifolding machine shown in the drawings is what is 35 known commercially as the Elliott-Fisher automatic feed machine. This machine is fully disclosed in the co-pending application of Harry A. Foothrap, Serial No. 33,797.

It includes a flat platen 1, located between 40 the front ends of rails 2, and carbon rolls 3, journaled at opposite sides of the platen. Between these rolls one or more carbon webs 3^a are led over the platen. A form guiding idler roller 4 extends between the rear ends 45 of the frame rails 2, and a removable carriage 5 carrying paper slitters 6 is located between the roller 4 and platen. Platen clamps 9 at the rear edge of the platen 1 serve to clamp the rear edges of the carbons 50 and the side edges of paper web 3^b led over the platen and interleaved with the carbon webs 3^a. The clamps 9 include upright posts 8.

A printing unit (not shown) is supported

upon the rails 2, and is removable over the 55 platen 1 to line space and letter space the record printed on the top sheet of paper and transferred by the carbons to the subjacent paper sheets.

The platen is depressible to release the 60 work from the platen clamps.

Upon the carriage 5 are supported in stepped arrangement, a plurality of transversely disposed carriers or fingers 10, having hinged keepers 11. To these fingers 10 65 are ordinarily attached by the keepers 11 the rear ends of floating carbon sheets which are usually employed in connection with fan fold webs which have been slit along the longitudinal folds by the slitters 6. This is 70 for the reason that the rough edges of the slit web multilates the edges of transverse carbons as the paper webs are fed forward over the platen.

The slitters 6 are disposed in groups at 75 opposite sides of the carriage 5, each group comprising a plurality of superposed short bars 12, spaced from each other and disposed obliquely of the line of paper feed as is well understood.

In accordance with my invention, provision is made for protecting or guarding from mutilation by the paper, the edges of the transverse carbons against which the slit edges of the fourfold web are drawn. 85 For each transverse carbon a guard 14 of paper or other suitable material is formed as shown in Figure 4. The guard is folded or doubled around one of the carbon fingers 10 to which it is secured by the keeper 11. 90

The number of guards employed depends of course on the number of carbons to be protected. The guards are held against lateral displacement when the platen 1 is depressed and are clamped to the platen by 95 the clamps 9 at a slight distance from the rear edges of the carbons when the platen is raised. This permits free adjustment of the carbons from one roll to the other. The guards 14 are notched as indicated at 15 100 to receive the posts 8 of the platen clamps 9 which thus retain the guards against longitudinal movement also. Since the guards extend or float in the direction of the paper feed they may be said to be floating carbon 105 guards.

It will be noted that the rear edge of each carbon web 3^a is enclosed by its guard the

end of which over and underlie the carbon edge which would otherwise be mutilated by the serrated slit edges of the paper.

From the foregoing it will be apparent that I have devised a combined carbon blind and guard and means for varying its location whereby it may be utilized either in a double capacity, i. e. to blind different areas of the carbon while at the same time separating intersecting edges of adjacent forms and their interleaved carbon, to prevent mutilation of the carbon, or in a single capacity, as a guard, functioning as aforesaid.

15 What I claim is:

1. In a manifolding machine, the combination with a flat platen for supporting movable forms and interleaved cross carbons, of a carbon guard including a pair of superposed flexible flaps wider than said forms, and guard carrying means for supporting the guard intermediate two of the forms to receive the associated interleaved carbon between said flaps, the location of said carrying means being variable whereby the guard may be utilized either in the double capacity of a blind preventing printing on the subjacent forms and a guard separating intersecting edges of the said carbon 30 and forms to prevent mutilation of the carbon by movement of the forms, or in the

single capacity of a guard for preventing mutilation of said edge in the manner aforesaid.

2. In a manifolding machine, the combination with a flat platen for supporting movable forms and interleaved cross carbons, of a carbon blind including a pair of superposed flaps adapted to be mounted between two of said forms in position to receive their associated carbon between said flaps and for variable location to vary the area of carbon blinded, said flaps being wider than said forms to separate intersecting edges of said forms and associated carbon in any location of said blind and thereby prevent mutilation of the carbon by rough edges of the forms, a carrier for mounting the blind in position between said two forms and variable as to location to vary the location of the blind, and means for clamping said flaps in fixed position at different points adjacent said edge of said carbon whereby the flaps are prevented from creeping during movement of the forms 50 and carbon and are at the same time free for separative play to permit free movement of the carbon therebetween.

In testimony whereof I have affixed my signature.

ALFRED JENSEN.
